UNITED STATES PATENT OFFICE.

EDWIN O. LAWRENCE, OF PORT JEFFERSON, NEW YORK, ASSIGNOR TO INTERNATIONAL SANITARY CESSPOOL COMPANY, OF PORT JEFFERSON, NEW YORK, A CORPORATION OF NEW YORK.

CESSPOOL.

1,204,462.

Specification of Letters Patent. Patented Nov. 14, 1916.

Application filed March 30, 1915, Serial No. 18,104. Renewed April 27, 1916. Serial No. 94,046.

To all whom it may concern:

Be it known that I, EDWIN O. LAWRENCE, a citizen of the United States, residing at Port Jefferson, in the county of Suffolk, State of New York, have invented certain new and useful Improvements in Cesspools; and I do hereby declare the following to be a full, clear, and exact description of the invention, such as will enable others skilled in the art to which it appertains to make and use the same.

This invention relates to cess-pools, and has for its object the provision of a cess-pool so constructed that it cannot be clogged by the accumulation of the solid matter forming a part of sewage flowing thereinto, and provided with means whereby the water is carried off rapidly and dissipated into the surrounding soil.

An important object is the provision of a cess-pool provided with drain orifices in its sides, whereby water may flow out easily while the entry of sand or the like is prevented.

Another object is the provision of a cess-pool so constructed that the overflow of water will be drawn from the center of the device thereby preventing clogging of the piping by either the solids which settle to the bottom of the device or by the grease which accumulates and floats on top of the water.

A further object is the provision of a cess-pool of this character which will be simple and inexpensive in manufacture and installation, durable and efficient in service, positive in action, sanitary and not offensive and a general improvement of the art.

With these and other objects and advantages in view, the invention consists in the novel construction and arrangement of parts to be hereinafter more fully described and claimed, and illustrated in the accompanying drawing, in which,

Figure 1 is an elevation of my device embedded in the ground and shown associated with the sink pipe and ventilator pipe of a house, Fig. 2 is a vertical sectional view therethrough, and Fig. 3 is a horizontal section taken along the line of the overflow pipes.

Referring more particularly to the drawing, the numeral 5 designates the main or cylindrical portion of my cess-pool which is formed of a plurality of cement blocks 6 trapezoidal in top plan and having inwardly

converging sides whereby a plurality of the blocks fitting snugly together will form a circle. Each block is provided with a plurality of vertically extending holes 7 adjacent its inner face and is further provided with a plurality of downwardly and outwardly extending holes 8 communicating with the holes 7 and extending through the outside of the block. When the cylindrical portion 5 of the cess-pool is thus formed, the holes 7 in each block align with the corresponding holes in the blocks immediately above and below it, thereby providing a plurality of vertically extending passages extending from the top to the bottom of the cylindrical portion 5 and disposed entirely around the periphery thereof. The upper portion or closure for the cess-pool is formed as an arch 9 formed of any suitable brick.

A pipe 10 extends from the waste pipe of the sink or other place to be drained and extends into the cess-pool at the skewback 11 or the junction of the arch 9 with the cylindrical portion 5, the pipe 10 being provided with a trap 12 for preventing the passage of gases or odors back up through the waste pipe of the sink.

In order to carry off the water flowing into the device through the pipe 10, I provide a pipe 13 extending within the device, passing through the bottom and extending down into either a layer or stratum of sand or gravel. The pipe 13 is provided with a point 14 for facilitating its penetration of the ground and is also provided with a plurality of holes 15 for the outlet of water. A T-coupling 16 is connected in the pipe 13 and has connected thereto a length of pipe 17 extending into the lateral arm of a T-coupling 18 which has its upper opening closed by a plug 19 and its lower portion connected with a pipe 20 extending downwardly to substantially the center of the cylindrical portion 5. The pipe 13 has connected therein a double T-coupling 21 to 100 the upper portion of which is connected a pipe 22 which carries a T-coupling 23 connected with an elbow 24 which has connected therewith a pipe 25 leading to the ventilation pipe commonly provided on a house. The lateral portion 26 of the coupling 23 is open to the air within the cess-pool.

Pipes 27 are connected with the lateral portions of the double T-coupling 21 and 110

extend into an annular passage 28 formed in the skewback 11 and communicating with the passages formed by the holes 7 in the blocks 6.

5 The operation of the device is as follows: The waste goes into the device through the pipe 10 and accumulates within the device, rising gradually until it reaches the skewback. The solid matter floats for a while 10 and then eventually settles to the bottom, while the greasy matter rises to the top. As the waste rises, the clear water at the central part will pass upwardly through the pipe 20 and into the pipe 17 and from there 15 into the pipe 13. When the level of the waste reaches the pipe 17, water will run out through the pipe 17 into the pipe 13 and into the layer of sand, gravel or water into which the pipe 13 extends, the waste 20 running out through the holes 15 and seeping through the ground. If the waste runs into the device more rapidly than it can be taken care of by the pipes 20 and 17, and if the pipe 13 should become filled on 25 account of saturation of the layer of sand or gravel at the end of the pipe 13, the waste will rise past the pipe 17 and to the pipes 27. When this happens the water passing through the pipe 17 will rise in the pipe 13 30 and pass through the pipes 27 into the annular passage 28 from whence it will flow downwardly through the vertical passages formed by the aligned holes 7 and through the holes 8, eventually seeping into and 35 through the soil surrounding the device.

The solid matter will not accumulate for any great length of time within the device, for the reason that it will decompose and be carried off with the water. The gases 40 formed by decomposition will pass through the coupling 26 and out through the pipe 25 which leads to the vent pipe extending above the roof of a house.

From the foregoing description and a 45 study of the drawing it will be apparent that I have thus provided a simple, novel and efficient cess-pool from which the waste will be drained quickly and efficiently into the surrounding soil and in which possibility of clogging is prevented and consequently the necessity for cleaning is eliminated.

It will be readily understood that I re-

serve the right to make various changes in the form construction and arrangement of 55 parts without departing from the spirit of the invention or limiting the scope of the subjoined claims.

Having thus described my invention, I 60 claim:

1. In combination with a waste pipe and a vent pipe, a cess-pool comprising a closed receptacle provided with vertical passages in its wall communicating with the outside of the receptacle at intervals, said passages 65 communicating at their upper ends with an annular passage, a pipe disposed within said receptacle and extending through the bottom thereof and into a layer of sand, said pipe being provided with outlet perforations, a pipe connected with said pipe and extending downward adjacent the center of the receptacle, and a pair of overflow pipes connected with said first named pipe and extending into said annular passage, said 75 first named pipe being further connected at its upper end with said vent pipe.

2. A cess-pool comprising a receptacle having its peripheral wall provided with a plurality of vertically extending passages 80 having inclined passages communicating therewith and extending to the outside of said receptacle, an inlet pipe connected with said receptacle and discharging thereinto, said inlet pipe being connected with a waste 85 pipe, a pipe within said receptacle, passing through the bottom thereof and extending into a layer of sand, an outlet pipe connected with said second named pipe and terminating at substantially the middle of the 90 receptacle, a pair of overflow pipes connected with said second named pipe above the point of connection of said third named pipe and extending into an annular passage in the wall of said receptacle communicating with said vertical passages, said second 95 named pipe being provided with an air inlet above said last named pipe, and a pipe connected with said second named pipe and communicating with the atmosphere.

100 In testimony whereof, I affix my signature, in the presence of two witnesses.

EDWIN O. LAWRENCE.
